UNITED STATES PATENT OFFICE

ERNEST DAVIS, OF SYRACUSE, NEW YORK, ASSIGNEE TO THE PROSPERITY COMPANY INC., OF SYRACUSE, NEW YORK, A CORPORATION OF NEW YORK

PRESS WITH PINION LEVERAGE

Application filed August 23, 1930. Serial No. 472,753.

This invention relates to garment or ironing press improvements and particularly to the actuating mechanism for such machines through which the motor moves one of the 5 pressing elements or jaws to open and close the press.

The principal object of the invention is to provide novel actuating mechanism for obtaining a mechanical advantage through 10 which the motor may apply pressure to the pressing elements.

A further object of the invention is to provide an actuating mechanism between the motor and the movable pressing element 15 which will change the mechanical advantage so as to obtain decreased speed and increased force as the movable pressing element reaches closed position.

A further object of the invention is to provide 20 actuating mechanism including gearing which is connected to the movable pressing element, and which is operated by a driving link connected to a motor.

Other objects and advantages of the invention 25 will appear and will be pointed out as the description proceeds.

The invention consists in the novel features and in the combinations and constructions hereinafter set forth and claimed.

In describing this invention, reference is had to the accompanying drawings in which like characters designate corresponding parts 30 in all the views.

Figure 1 is a side elevation, partly in section, 35 of a pressing machine showing my invention applied thereto.

Figure 2 is a schematic showing, mostly in section, of the control mechanism for the press shown in Figure 1.

Figure 3 is a detailed view of the driving 40 link, and gear means associated therewith, used on the pressing machine shown in Figure 1.

Figure 4 is a top view, partly in section, 45 of the mechanism shown in Figure 3.

The invention is designed primarily for use with pressing machines having a movable pressing jaw or head 11 secured to a yoke 12 which is pivotally mounted at 13 on up- 50 standing portion of a pressing machine frame

14. The pressing head 11 is movable toward and from a fixed pressing element or buck 15 to close and open the press. The buck 15 is supported by a neck 16 which is mounted on the pressing machine frame 14. 55

The yoke 12 is pivotally connected at 20 to a driven link 21. The driven link 21 is pivotally connected at 23 to spaced link members 25 which are rigidly secured to a pinion shaft 26. A pinion 28 is rigidly secured to the pinion shaft 26 and the pinion shaft 26 is rotatably mounted in a yoke 30 which is formed on the end of a bell crank 32. The bell crank 32 is pivotally mounted on a shaft 34 which is secured to the pressing machine 65 frame 14.

A driver lever 35 is pivotally mounted on the shaft 34 and is provided with a slot 36 near one end thereof. The driver lever 35 is provided with a gear segment 38 at one 70 end and the pinion 28 meshes with the teeth of gear segment 38. A second driver lever 39 is mounted on the shaft 34 and is identical in construction with the driver lever 35, with the exception that it does not have an end portion with the gear segment 38 formed thereon. The link members 25 operate in the slots 36 of the driver levers 35 and 39, see Figures 3 and 4. The lower end of the slots 36, designated as 40, provides a stop to limit the downward movement of the links 25 in the slots 36. 75

The driver levers 35 and 39 are secured together at their forward ends by pins 42 and 44. The lower end of a piston rod 45 is pivotally mounted on the pin 44 and a connecting member 47 forms a pivotal connection between the pin 42 and a spring 50. 80

The spring 50 is connected at its upper end at 51 with the pressing machine frame 14 and normally holds the driver levers 35 and 39 in upraised position, as shown in Figure 1. A spring 52 which is connected to the yoke 12 at one end and to the pressing machine frame 14 at the other end, normally holds the press in open position. A fluid motor 53 is oscillatably mounted at 55 on the pressing machine frame 14 and operation of the fluid motor 53 moves the piston rod 45 to actuate the driving levers 35 and 39 to rock 90

push button 94 operates a bell crank 95 which transmits motion of the push button 94 to the rocker arm 86 to operate the valves 81 and 82 in the valve casing 79. A spring 96 holds the bell crank 95 and push button 94 in normal inoperative position.

The valve casing 78 contains an exhaust valve 102 which is provided with a valve stem 105 extending through the end of the 10 valve casing 78. A rocker arm 106 contacts with the end of the valve stem 105 to move the exhaust valve 102 into closed position. The rocker arm 106 is pivotally mounted at 15 107 on a bracket extending from the valve casing 78. A diaphragm chamber 109, formed on the lower side of the valve casing 78, contains a diaphragm 110. A plunger 112 extends through the end of the diaphragm chamber 109 and when pressure is 20 applied behind the diaphragm 110, the plunger 112 will be operated to move the rocker arm 106 to close the exhaust valve 102, or hold the exhaust valve 102 in closed position. A push button 114 operates a bell 25 crank 115 which transmits motion from the push button 114 to the rocker arm 106 to operate the valve 102 in the valve casing 78. A spring 116 holds the bell crank 115 and push button 114 in normal inoperative position. 30 The valve casing 79 is connected with a suitable source of working fluid by a fluid supply line 120. When the push button 94 is operated to open the intake valve 81 and 35 close the exhaust valve 82, working fluid will flow from the fluid supply line 120, around the open intake valve 81, through the valve casing 79, branch pipe 76, and pipe 74 to the cylinder 70 to operate the fluid motor 53 to 40 close the press, as previously described. It is necessary that the push button 114 be operated to close the exhaust valve 102, since if this valve 102 is left open, working fluid from the pipe 74 may escape through the 45 branch pipe 75 and past the open exhaust valve 102, thus preventing pressure from building up in the pipe 74 and cylinder 70 to operate the motor 53. This control mechanism for supplying working fluid to the motor 53 is of the conventional two-hand control type and forms no part of the present 50 invention.

The valves in the valve casings 78 and 79 are locked in operated position by conventional means such as a port opening 122 which is located in the wall of the cylinder 70 at a point near the end of the stroke of the piston 71 so that the piston 71 will uncover the port opening 122 when the press 60 moves into closed position. When the piston 71 uncovers the port 122, working fluid will flow into the chamber 125 and through the pipe 126 and pipes 128 and 129 to the diaphragm chambers 109 and 89, respectively, 65 to actuate the diaphragms therein and lock

the valves in the valve casings 78 and 79, respectively, in operated position.

The bell crank 60 is pivotally mounted at 135 on the pressing machine frame 14. The spring 62 normally holds the bell crank 60 70 in contact with a stop lug 136 which is formed on the pressing machine frame 14. A diaphragm chamber 138 is mounted on the pressing machine frame 14 and contains a diaphragm 140. The diaphragm 140 operates a plunger 142 which extends through the end of the diaphragm chamber 138 and contacts with the upper end of the bell crank 60. A pipe 144 connects the pipe 129 with the diaphragm chamber 138 and when the piston 71 uncovers the port opening 122 to supply working fluid through the pipe 129 to the diaphragm chamber 89, as previously described, working fluid will also pass through the pipe 144 to actuate the diaphragm 140 in the diaphragm chamber 138. When the diaphragm 140 is thus actuated, the plunger 142 will rock the bell crank 60 about the pivotal connection 135 and raise the latch 59 75 out of contact with the pin 58, thus releasing the bell crank 32. Since the diaphragm 140 is operated by working fluid which escapes through the port opening 122, and since the port opening 122 will not be uncovered by the piston 71 until the press has reached 80 closed position, it is obvious that the pin 58 will always be released by the latch 59 at the proper time during the closing of the press.

Means are provided to open the press by 100 relieving the pressure in the diaphragm chambers 89 and 109. These means include a handle 150 which opens an exhaust valve 151 which is normally held closed by a spring 153. The exhaust valve 151 is located in a 105 valve casing 154 which is connected by pipe 155 with the pipe 126 through which working fluid is supplied to the diaphragm chambers 89 and 109.

Operation of the mechanism is as follows:—

With the press opened and the parts in the positions shown in Figure 1, the operator will depress the push buttons 94 and 114 to operate the valves in the valve casings 79 115 and 78, respectively. Working fluid from the fluid supply line 120 will flow around the open intake valve 81, through the valve casing 79, and branch pipe 76 to the pipe 74. The exhaust valve 102 being closed, pressure 120 will build up in the pipe 74, branch pipe 75, and cylinder 70 to operate the piston 71 and piston rod 45 of the fluid motor 53. The piston rod 45 will move downwardly and rock the driver levers 35 and 39 in a clockwise direction about the shaft 34. The gear segment 38 on the driver lever 35 will move upwardly, about the shaft 34 as a center, and will rotate the pinion 28 in a clockwise direction since the pinion is held against move- 125 130

ment about the axis of the shaft 34 by the latch 59 which engages the pin 58 of the bell crank 32, in which the pinion shaft 26 is journaled. The gear segment 38 will rotate 5 the pinion 28 and move the link members 25 about the axis of the shaft 26 until the toggle, composed of driven link 21 and link members 25, is moved into substantially straightened position and the pressing head 11 is 10 in contact, or substantially in contact, with the buck 15. When the pressing jaws 11 and 15 are in contact, or very nearly in contact, the piston 71 will uncover the port 122 in the wall of the cylinder 70 and working fluid 15 will pass through the port opening 122, chamber 125, pipe 126, and pipes 128 and 129 to operate the diaphragms in the diaphragm chambers 109 and 89, respectively, to lock the valves in the valve casings 78 and 79 in 20 operated or closed-press position. When working fluid is thus supplied to the pipe 129 it will also flow through the pipe 144 to actuate the diaphragm 140 in the diaphragm chamber 138 to move the plunger 142 to the left, in Figure 2, and rock the bell crank 60 in a counter-clockwise direction about the pivotal connection 135. This movement of the bell crank 60 will raise the latch 59 and release the pin 58. When the latch 30 59 releases the pin 58, the bell crank 32 is free to pivot about the shaft 34 and the pinion 28 is free to act as a planet gear, though in actual practice the link members 25 will usually be in contact with the lower ends 35 40 of the slots 36 and the load exerted by the driven link 21 against the link member 25 will prevent the pinion 28 from operating as a planet gear.

When the operator wishes to open the press, 40 he will actuate the handle 150 which opens the exhaust valve 151 in the valve casing 154 and permit working fluid to escape from the diaphragm chambers 138, 89, and 109, through the pipe 155 which connects with the 45 pipe 126 through which working fluid is supplied to all of the diaphragm chambers by means of the branch pipes, previously described. An orifice 156 is provided in the pipe 126 so that working fluid will escape 50 from the pipe 126, through the pipe 155, valve casing 154, and around the open exhaust valve 151, faster than it can be supplied to the pipe 126 from the port opening 122 and chamber 125.

When the pressure in the diaphragm chambers 89 and 109 is thus reduced, the spring 84 will restore the valves in the valve casing 79 to normal position with the intake valve 81 closed and the exhaust valve 82 open, 60 and the exhaust valve 102 will be free to open under influence of the pressure in the pipe 78 and valve casing 78. When the exhaust valves 82 and 102 are thus opened, working fluid will escape through the fluid motor 53 65 through the pipe 74, branch pipes 75 and 76, valve casings 78 and 79, and past the open exhaust valves 102 and 82. When the pressure in the fluid motor 53 is thus reduced, the springs 50 and 52 will move the press actuating mechanism back into open-press position, as shown in Figure 1. The spring 50 will rock the driver levers 35 and 39 in a counter-clockwise direction about the shaft 34 and the bell crank 32 will partake of this same movement until the upstanding arm of the bell crank contacts with a spring 160, not previously mentioned, which provides a resilient stop member to limit further reverse movement of the bell crank 32. When the bell crank 32 can move no further in a counter-clockwise direction, the further movement of the driver levers 35 and 39 will cause the gear segment 38 to rotate the pinion 28 in a counter-clockwise direction, thus breaking the toggle out of straightened position and causing the link member 25 to move upwardly in the slots 36. After the toggle, composed of driven link 21 and link members 25, has moved a slight distance away from straightened position, the force of the spring 52, exerted downwardly through the driven link 21, will cause the link member 25 to rotate the pinion shaft 26 and pinion 28 in a counter-clockwise direction until the link member 25 comes into contact with the upper end of the slots 36, in which position it is shown in Figure 1.

From the above description it will be apparent that I have provided a novel actuating mechanism for a pressing machine which employs gear means for transmitting motion from the motor to the movable pressing element, and which automatically changes the mechanical advantage between the motor and the movable pressing element, to obtain greater force on the movable pressing element, as the press reaches closed position. The invention is illustrated in its preferred embodiment but changes and modifications may be made without departing from the spirit of the invention as set forth in the appended claims.

What I claim is:

1. In a pressing machine in combination, cooperative pressing elements, one of which is movable with respect to the other to open and close the press; operating mechanism for the movable pressing element including motor means; a driving lever operated by the motor means; a gear segment mounted on the driving lever; gearing meshing with and driven by the gear segment; link means connected with the gearing and with the movable pressing element and driven by power transmitted through relative rotation of the gearing and gear segment to initially close the press; and means for shifting the gear transversely of its axis to apply heavy pressure to the pressing elements.
2. In a pressing machine in combination,

cooperative pressing elements, one of which is movable with respect to the other; operating mechanism for the movable pressing element including a driving lever pivotally mounted between the ends thereof; motor means connected to the driving lever at one side of the pivotal mounting; a gear segment mounted on the driving lever on the other side of the pivotal mounting; a gear and means on which said gear is rotatably mounted in position to mesh with the gear segment on the driving lever; a crank connected with and driven by the gear; link means connecting the crank with the movable pressing element; and means for moving the means on which the gear is rotatably mounted to apply heavy pressure to the pressing elements.

3. Actuating mechanism for a pressing machine including in combination, a driving lever, a driven link, gearing connected to said lever and link for transmitting power from the driving lever to the driven link a predetermined distance, means for preventing further operation of the gear drive, and means for moving the gearing as a unit after the link has moved said predetermined distance.

4. A pressing machine in combination, cooperative pressing elements, one of which is movable with respect to the other, operating mechanism for the movable pressing element including motor means, a driving lever operated by the motor means, a gear segment mounted on the driving lever, gearing meshing with and driven by the gear segment, link means driven by said gearing and connected with the movable pressing element, means to prevent further rotation of the gearing after the pressing elements have moved into initial closed position, and means for moving the gearing to apply heavy pressure to the pressing elements.

5. A garment pressing machine in combination cooperative pressing elements, one of which is movable toward and from the other to open and close the press; motion transmitting means connected with the movable pressing element and including a link; a pivotal mounting for said link; a gear carried on the pivotal mounting and connected with said link; operating mechanism for rotating the gear to swing the link to initially close the press and for shifting the pivotal mounting transversely of its axis to apply heavy pressure to the pressing elements; and means to hold the pivotal mounting against said shifting during initial closing of the press.

6. In a garment pressing machine in combination cooperative pressing elements, one of which is movable toward and from the other to open and close the press; motion transmitting means connected with the movable pressing element and including a link; a pivotal mounting for said link; a gear carried on the pivotal mounting and connected

with said link; operating mechanism for rotating the gear to drive the link to initially close the press and for shifting the pivotal mounting transversely of its axis to apply heavy pressure to the pressing elements; means to hold the pivotal mounting against said shifting during initial closing of the press; and means to automatically release said holding means when the press is operated into substantially closed position.

7. A garment or ironing press comprising a coacting head and buck, a press lever carrying the head, a toggle having one link pivotally connected with the press lever, a gear rigidly attached to the other link, a lever including a rack meshing with the gear, and motor means to operate the last named lever.

8. A garment or ironing press comprising a coacting head and buck, a press lever carrying the head, a toggle having one link pivotally connected with the press lever, the toggle being disposed uprightly and having a lower link the bottom end of which is carried on a shaft, a pinion mounted rigidly on the shaft, a lever having an upright slot in which the shaft is confined, a rack formed on the lever adjacent the slot and engaging the pinion, and motor means operatively connected with the lever.

9. A garment or ironing press comprising a coacting head and buck, a press lever carrying the head, a toggle having one link pivotally connected with the press lever, a motor, a power lever means including a pair of spaced lever parts rigidly secured together and operatively connected with the motor, a gear rack formed on one of the lever parts, a pinion meshing with the gear rack, the other end of the toggle being attached to the pinion, lever means operatively carried between the spaced lever parts, said pinion being mounted on said last named lever means, and means to arrest the movement of said last named lever means during preliminary closing movement of the press.

In testimony whereof, I have hereunto signed my name, at Syracuse, in the county of Onondaga, and State of New York, this 28th day of August, 1930.
